UNITED STATES PATENT OFFICE.

WILLIAM E. BAKER, OF ASHER, OKLAHOMA.

DRINK DISPENSER.

Application filed January 27, 1927. Serial No. 164,052.

The invention generally relates to liquid dispensing apparatus and primarily has for its object to provide a simple and economically constructed drink dispenser in which means is provided for automatically depositing a drinking cup and a measured drink in position for being readily partaken of by the person so desiring and who has properly manipulated the control lever.

10 In its more detailed nature the invention seeks to provide an apparatus of the class described comprising a liquid reservoir, means for measuring a predetermined quantity of the liquid upon demand, a nested cup compartment, means for depositing the cups individually in position to receive the measured drink, and a single control lever and connections for operating the cup positioning and drink depositing means in desired sequence.

With the above and other objects in view that will hereinafter appear, the invention further resides in the novel details of construction, combination and arrangement of parts, all of which will be first fully described, then be particularly pointed out in the appended claims, reference being had to the accompanying drawings, in which:

Figure 1 is a perspective view illustrating 30 the invention.

Figure 2 is a front elevation illustrating the invention, parts being broken away and in section.

Figure 3 is a horizontal section taken on 35 the line 3—3 on Figure 2.

Figure 4 is an enlarged detail section illustrating the drink quantity controlling and delivering means.

Figure 5 is a detail section illustrating 40 the cup delivery mechanism.

Figure 6 is a view similar to Figure 5 showing the function of the parts in releasing a sticking cup.

Figure 7 is a detail plan view illustrating 45 one simple type of coin control which may be employed.

In the drawings, in which like numerals of reference indicate like parts in all of the figures, 1 indicates the main housing which 50 is equipped with a suitably mounted horizontal partition or floor 2 to divide the same into upper and lower compartments, the upper compartment serving to accommodate the positioning of the liquid reservoir and 55 an ice chamber 3 for suitably cooling the

liquid in a manner hereinafter again referred to.

The upper compartment of the housing or cabinet is provided with a hinged lid or cover 4 through which access may readily be had into the upper compartment, and to prevent unauthorized tampering, the cover may be lock equipped as at 5. The cabinet is also provided at one side with a door 6 through which cracked ice may be filled into 65 the ice chamber 3.

The front face of the cabinet, adjacent each corner, is equipped with column or pedestal simulations 7 and 8, the former serving to accommodate a nested cup compartment 9 which discharges, at its lower end, into a nested cup compartment 10 which, in the practical development of the invention, may be constructed to simulate a base for the column 7. The compartment 70 10 is provided with a suitable spring hinged equipped door 11 which may be provided with a suitable window or sight 12 through which the interior of the compartment may be readily viewed.

The remaining simulated column 8 accommodates a liquid indicator compartment and is window or sight equipped as at 14 so that the interior thereof may be viewed for a purpose later to be described. The base 85 portion beneath this column is hollowed out and forms a suitable money compartment 15 equipped with a coin receiving tray 16 and a suitable hinge and lock equipped door through which access may be had to the 90 said compartment.

A liquid reservoir 17 is mounted in the upper compartment of the cabinet which may be constructed generally in any suitable manner but which includes at its lower extremity a suitable discharge throat 18 which seats in the receiving throat 19 which is suitably gasketed as at 20 and forms the upper extremity or receiving neck 21 of a cooling coil 22 which is coiled about in the ice 100 chamber 3 hereinbefore referred to.

The lowermost or discharge end of the coil 22 discharges into a union 23 which serves to connect the said discharge end with the valve neck 24, a suitable cross brace 25 being 105 secured in the cabinet beneath the partition floor 2 to assure a strong mounting for the valve neck and coil end to overcome weakening tendency that might cause leakage.

The valve neck 24 extends a considerable 110

distance beneath the partition floor 2 and is equipped with a relatively large discharge port and valve seat 26.

A measuring cup or vessel 27 is provided for cooperating with the valve neck 24 and the said vessel is provided at its upper end with a counterbore 28 adapted to slidably fit the depending portion of the neck 24 to permit a degree of vertical sliding movement 10 of the measuring vessel on the said neck. The vessel 27 is provided at its lower end with a relatively small discharge throatway which provides a suitable valve seat 29 and which is formed in the depending neck 30 15 formed on the lower end of the said vessel.

A double valve 31 is provided and is equipped with a relatively large valve element 32 at its upper end for seating in the valve seat of the neck 24 and a lower valve 20 element 33 for seating in the measuring vessel valve seat 29.

By reference to Figures 2 and 4 it will be observed that when the parts are in the normal position the upper valve element 32 25 will be seated in the upper valve seat 26 preventing flow of liquid out of the coil into the measuring vessel 27. In this case, the measuring vessel is at its lowered position and the lower valve element 33 is unseated from 30 the lower valve seat 29, leaving the discharge throatway of the measuring vessel open. A keeper head 34 is secured in the lower end of the double valve member in such a manner as to support the measuring vessel when at 35 its lowered position just described and prevent disassociation of the parts. By moving the measuring vessel 27 upwardly on the neck 24 in a manner later to be described, the lower valve element 33 will first be 40 caused to seat closing the discharge throatway of the said vessel and on continued vertical movement the upper valve element 32 will next be unseated to permit flow of a sufficient quantity of liquid into the measuring vessel to fill the same. When the measuring vessel is again lowered the reverse 45 action will take place and the upper valve element will be seated and the lower valve element unseated and the measured quantity 50 of liquid within the vessel permitted to flow therefrom through the neck 30.

The neck 30 of the measuring vessel discharges into the receiving end of a delivery tube 35, the discharge end 36 of which is 55 extended into the service compartment 10 to deliver the contents of the measuring vessel into a suitable receptacle (a sanitary drinking cup) positioned in that compartment. For suitably raising and lowering 60 the measuring vessel 27 to accomplish the functions just described I provide a bail 37 pivoted as at 38 to the housing beneath the floor 2 and having the bail arms thereof angled in the manner illustrated in Figure 65 2 of the drawings and with the extremities

thereof pivoted as at 39 to the trunnions 40 which project from opposite sides of the vessel 27.

Another bail 41 has its extremities pivoted as at 42 to the angles of the bail 37 70 and as at 43 to the inner end of an operating lever 44 which is itself pivoted as at 45 to a suitable support provided in the housing and which is extended through a suitable slot in the front face of the housing and 75 equipped with an operating handle 46.

The coin compartment 15 may be provided with a suitable floor or rest 47 and a side slotway 48, and the rest 47 may also have a coin drop slot 49. A slide 50 is slidable 80 on the rest 47 and through the slotway 48 and has its projected end slot and pin connected as at 51 to the extended end of the lever 44 so that the said slide will be reciprocated as the lever is oscillated. 85

The slide 50 is provided with a coin depression 52 leading into a coin slot 53 which, in the normal position of the parts, is half covered or more than half covered in the side slotway 48 so that in order to insert a coin into the slot it is necessary to lay it in the depression 52 and work it into the slot 53 through the slotway 48. 90

A fixed stop 54 is provided and the slide 50 is equipped with a spring trigger 55 95 which normally engages the stop 54 and renders it impossible to move the lever 44 to force the slide 50 inwardly. The trigger 55 is extended into the coin slot 53 to form a release dog 56 which when a coin is inserted into the slot 53 is displaced and the spring trigger 55 removed from engagement with the stop 54 to thus permit movement of the lever and forcing of the slide inward so that the coin in the slot 53 may drop into the tray 16. This movement of the lever 100 effects a raising of the measuring vessel 27, as hereinbefore described, and effects the measuring of a predetermined quantity of liquid. 105

A plurality of the usual type of sanitary drinking cups 57 are deposited into the compartment 9 in nested relation with their flanges bearing the usual spaced relation. In the service compartment 10 are provided 110 opposed sets of upper and lower delivery members 58 rotatably mounted as at 59 and each set of which includes toothed sectors 60 adapted to engage to cause the upper and lower members of each set to rotate in opposite directions when motion is imparted to one member of each set. 115

The lower members of the delivery sets are each equipped with rest lugs 61 adapted to fit under the flange 62 of the lowermost one 120 of the nested cups to support the entire stack of cups when the parts are in the normal position. The members 58 of each set are equipped with separator cam surfaces 63, those of the upper members being effective 125 130

in an upward direction and those of the lower members being effective in a downward direction.

A crank 64 is secured to the nearest upper 5 and the opposite lower member 58, said cranks being link-connected as at 65 to move together and with the operating lever 44.

Thus, each time the lever is moved to the left to elevate the measuring vessel 27 and 10 to fill it with a measured quantity of liquid, the members 58 are moved to the position illustrated in Figure 6 to force the lowermost cup downwardly off of the stack of 15 cups and to simultaneously slightly raise the remainder of the stack of cups, thus serving not only to deposit a cup into the compartment 10 in position for receiving the measured quantity of liquid but also to assure stripping of that cup from off the stack should 20 tendency to stick exist.

A drain or conduit 66 is connected as at 25 67 into the discharge end of the coil 22 and connects with the drain pipe 68 through a suitable cutoff or control valve 69 by manipulation of which the contents of the coil may 30 be drained when desired. An indicator tube is connected with the conduit 66 above the control valve proper and is extended up into the column 8 to be viewed through the window thereof for ascertaining the level of liquid in the reservoir.

To assure positive return of the lever 44 to its normal position and consequently the 35 normal position of the measuring vessel and cup discharging elements 58, a suitable retractile spring 71 may be connected to the housing and to the angle of the bail 37 so that the same will exert its tendency downward on the said bail.

40 In operation when it is desired to draw a regular quantity of liquid refreshment from the cabinet the operator places the proper coin into the depression 52 and from there into the coin slot 53, thus releasing the stop and permitting movement of the lever 44. When the lever 44 is moved to the left the measuring vessel 27 is elevated and the double valve actuated to permit filling of the vessel. During this operation, the elements 45 58 have been actuated to cause the depositing of a drinking cup in the compartment 10 beneath the discharging end 36 of the delivery pipe 35. The lever is again moved to the right back to its normal position, causing the measuring vessel to be lowered to its normal position and the double valve reseated to close communication from the coil into the measuring vessel and to open communication from the said vessel into the delivery tube when the measured drink will pass through the said delivery tube and into the deposited cup. The operator now has but to open the sanitary door 1 and partake of the drink automatically deposited therein. 55 60 65 While I have disclosed one type of coin

controlled mechanism it is to be understood that any suitable type of coin mechanism may be employed or the device may even be used without a coin control, if desired.

From the foregoing description, taken in 70 connection with the accompanying drawings, it is thought the complete construction the manner of operation and advantages of my invention will be readily apparent to those skilled in the art to which it relates. 75

What I claim is:

1. In liquid dispensing apparatus, a liquid supply duct including an outlet neck having a relatively large outlet port, a measuring vessel vertically slidably mounted on said neck and having a relatively small discharge port, a double valve adapted to close the outlet port and open the discharge port when the vessel is in its lowered position and to open the outlet port and close the discharge port when the vessel is in its raised position, a stop head depending from the double valve to sustain the vessel when in its lowered position, and means to raise and lower the vessel for the purposes specified. 90

2. In liquid dispensing apparatus, a liquid supply duct including an outlet neck having a relatively large outlet port, a measuring vessel vertically slidably mounted on said neck having a relatively small discharge port, a double valve adapted to close the outlet port and open the discharge port when the vessel is in its lowered position and to open the outlet port and close the discharge port when the vessel is in its raised position, a stop head depending from the double valve to sustain the vessel when in its lowered position, a rockable lever, trunnions projecting from opposite sides of the vessel, a bail pivoted to a fixed support and having angled arms pivoted at their free extremities to the trunnions, and a bail pivoted to one lever end and to the angled arms the pivot connections being made in the angles, whereby when the lever is rocked the vessel will be raised to measure a quantity of liquid and when lowered will dispense the measured quantity of liquid. 100

3. In liquid dispensing machines, liquid measuring and delivering mechanism comprising a liquid supply duct having an outlet, a valve controlling the supply duct outlet, a measuring vessel cooperative with the supply duct outlet to receive liquid therefrom when the valve is opened and itself 115 having a discharge port, said valve including a stem and an auxiliary valve within said vessel, said auxiliary valve cooperating with the vessel's discharge port, and a manually operable device for raising and lowering said vessel to alternately seat and unseat said first mentioned valve and its auxiliary valve whereby, when said cup is raised, said auxiliary valve will be seated to close said discharge port and said first mentioned 120 125 130

valve will be opened to permit filling of the vessel for the purposes specified.

4. In liquid dispensing machines, liquid measuring and delivering mechanism comprising a liquid supply duct including a valve controlled outlet, a measuring vessel slidably mounted in cooperative relation to the duct outlet and having a discharge port,

a double valve member adapted to open the outlet and close the port or open the port and close the outlet accordingly as said vessel is moved in one direction or the other, and means for moving the vessel as and for the purposes specified. 10

WILLIAM E. BAKER.
